Primary Examiner—Doris Clark

[57] CLAIM

The ornamental design for an oil spill barricade, as shown and described.

DESCRIPTION

FIG. 1 is a front elevation view.

FIG. 2 is a rear elevation view.

FIG. 3 is a top plan view.

FIG. 4 is a bottom plan view; and,

FIG. 5 is a side elevation view.

The oil spill barricade is broken near one end to indicate indefinite length.
